US0D1054771S

(12) **United States Design Patent** (10) Patent No.: **US D1,054,771 S**
(45) Date of Patent: ** Dec. 24, 2024

(54) **FOOD PREPARATION DEVICE**(71) Applicant: **SHARKNINJA OPERATING LLC**,
Needham, MA (US)(72) Inventors: **Joshua D. Anthony**, North Billerica,
MA (US); **Dan Kestenbaum**,
Brookline, MA (US); **Gary V.**
Palladino, Roslindale, MA (US)(73) Assignee: **SharkNinja Operating LLC**,
Needham, MA (US)(**) Term: **15 Years**(21) Appl. No.: **29/928,172**(22) Filed: **Feb. 8, 2024****Related U.S. Application Data**(63) Continuation of application No. 29/733,267, filed on
Apr. 30, 2020, which is a continuation of application
No. 29/694,045, filed on Jun. 6, 2019, now Pat. No.
